UNITED STATES PATENT OFFICE.

HEINRICH DEGENER, OF BERLIN, GERMANY, ASSIGNOR TO MERGENTHALER LINOTYPE COMPANY, A CORPORATION OF NEW YORK.

MATRIX-SETTING AND TYPE-LINE-CASTING MACHINE.

1,074,843.

Specification of Letters Patent.

Patented Oct. 7, 1913.

Application filed January 14, 1911. Serial No. 602,562.

To all whom it may concern:

Be it known that I, HEINRICH DEGENER, residing at 26 Hollmannstrasse, Berlin, S. W., a subject of the King of Prussia, German Empire, manager, having invented certain new and useful Improvements in or Relating to Matrix-Setting and Type-Line-Casting Machines, do hereby declare that the following is an exact specification of the same.

The present invention relates to a casting carriage of matrix setting and type line casting machines of the Mergenthaler system for the purpose of producing mixed copy, in which the matrices received in the collector in their elevated position rest during the casting of the line on a bar adjustable in the casting slide, which bar is moved for the transfer of the matrices to the lifter in such a manner that the matrices at the beginning of the line are immediately brought into their lower position, the other matrices following according to the advance of the line, as particularly described in my Letters Patent No. 1,011,590. In this arrangement it has proved a drawback, that in consequence of the movement of the bar between the top edge of the lower ears of the lower and the bottom edge of the lower ears of the upper matrices, the matrices will place themselves obliquely to the transverse plane of the line of matrices and brake the bar with their ears.

The present invention has the object of avoiding this oblique adjustment of the matrices.

In the accompanying drawing Figure 1 is a section through the casting slide shortly before the same has reached its highest position, Fig. 2 is a corresponding front elevation, Fig. 3 is a front elevation of the casting slide in its highest position after the release of the bar, Figs. 4 and 5 show two different constructions of the slide *h*.

The casting slide itself, the arrangement of the bar and the arrangement for operating this bar are the same as with the prior patent noted above. In addition thereto a slide *h* is here provided on the bar *e*, which latter is intended to return the spacing wedges to their ordinary length, that is to say, to return to normal position the movable members of the spacers which have been elevated during justification, in the manner well known in the art. This slide *h* has a

bifurcated form, is guided on both sides of the bar *e* and possesses arms *i* pointing downward. The slide *h* is adjustable on bar *e* and can be fixed in any position on the same, it being adjustably connected thereto by the engagement of its inturned flanges in the longitudinal grooves *g*, *g*, and a transversely located binder screw *s* being provided to hold it in the desired position. The arms *i* of the slide *h* will engage behind the outermost matrix when the casting carriage is moved into its upper position, and hold such matrix, so that, when the bar *b* is subsequently moved, by the bell crank lever *p* the matrices cannot be carried along and placed obliquely. For facilitating the adjustment of the slide *h* a graduation *k* may be provided on bar *e* or on the slide itself.

In order to prevent the matrices from being moved obliquely within the space cleared by the spacing wedges being drawn out, the slide may also be provided with an elastic buffer *m*, as shown in Fig. 4 of the drawing or with a surface of such a curvature *n* that it will compress the row of matrices on the casting carriage rising, and again close the space between the single matrices occupied by the spacing wedges. A slide constructed in such a manner is shown in Fig. 5 of the drawing.

Having thus particularly described and ascertained the nature of my invention and in what manner the same is to be performed, I declare that what I claim is:

1. In a matrix setting and line casting machine of the Mergenthaler type in combination a movable casting carriage having a bar holding the matrices in the upper level, means to move said bar longitudinally, a fixed part of the machine and a slide arranged on said fixed part engaging behind the outermost matrix, when the casting carriage is moved into its upper position and before the bar begins to move.

2. In a matrix setting and line casting machine of the Mergenthaler type in combination a movable casting carriage having a bar holding the matrices in the upper level, means to move said bar longitudinally, a bar intended to return the spacing wedges to their ordinary length and a slide arranged on said bar and adjustable thereon, the said slide engaging behind the outermost matrix, when the casting carriage is moved into its

upper position and before the bar begins to move.

3. In a matrix setting and line casting machine of the Mergenthaler type in combination a movable casting carriage having a bar holding the matrices in the upper level, means to move said bar longitudinally, a bar intended to return the spacing wedges to their ordinary length and a slide arranged on said bar and adjustable thereon, the said slide having arms engaging behind the outermost matrix, when the casting carriage is moved into its upper position and before the bar begins to move.
4. In a matrix setting and line casting machine of the Mergenthaler type in combination a movable casting carriage having a bar holding the matrices in the upper level, means to move said bar longitudinally, a bar intended to return the spacing wedges to their ordinary length, a slide arranged on said bar and adjustable thereon, the said slide engaging behind the outermost matrix when the casting carriage is moved into its upper position and before the bar begins to move and means for fixing the slide in any position.

5. In a matrix setting and line casting machine of the Mergenthaler type in combination a movable casting carriage having a bar holding the matrices in the upper level, means to move said bar longitudinally, a bar intended to return the spacing wedges to their ordinary length and a slide arranged on said bar and adjustable thereon, the said slide engaging behind the outermost matrix of the line, said slide being provided with means for compressing the matrix line in such a manner that the spaces produced by the withdrawal of the spacing wedges within the line are again closed up.

6. In a matrix setting and line casting machine of the Mergenthaler type in combination a movable casting carriage having a bar holding the matrices in the upper level, means to move said bar longitudinally, a bar intended to return the spacing wedges to their ordinary length and a slide arranged on said bar and adjustable thereon, the said slide having an arm engaging behind the outermost matrix, when the casting carriage is moved into its upper position and before the bar begins to move, said

arm having a surface of such curvature that it compresses the matrix line in such a manner that the spaces produced by the withdrawal of the spacing wedges within the line are again closed up.

7. In a matrix setting and line casting machine of the Mergenthaler type in combination a movable casting carriage having a bar holding the matrices in the upper level, means to move said bar longitudinally, a bar intended to return the spacing wedges to their ordinary length, a slide arranged on said bar and adjustable thereon, the said slide engaging behind the outermost matrix when the casting carriage is moved into its upper position and before the bar begins to move and the said bar being provided with a graduation for facilitating the adjustment, substantially as described.

8. In a typographical machine, the combination of the casting elevator to convey the assembled matrix line upward for distribution, and a device fixed to the framework of the machine and located in position to engage the end of the line as the elevator moves into its upper position.

9. In a typographical machine, the combination of the casting elevator to convey the assembled matrix line upward for distribution, and a device fixed to the framework of the machine and comprising a yielding member located in position to engage the end of the matrix line as it moves into its upper position and compress it endwise.

10. In a typographical machine, the combination of the first elevator and means to level the matrices therein, with a stationary device to engage the end of the matrix line when the elevator arrives in the leveling position.

11. In a typographical machine, the combination of the first elevator having means to sustain the matrices at different levels, with means to level the matrices therein, together with a stationary device to engage the end of the matrix line when the elevator arrives in the leveling position.

In testimony whereof I have affixed my signature in presence of two witnesses.

HEINRICH DEGENER.
